UNITED STATES PATENT OFFICE.

FRANCIS M. STAMBAUGH, OF ST. LOUIS, MISSOURI, ASSIGNOR TO THE AMERICAN BRAKE COMPANY, OF ST. LOUIS, MISSOURI, A CORPORATION OF MISSOURI.

DRILL-PRESS.

No. 824,829.

Specification of Letters Patent.

Patented July 8, 1906.

Application filed March 7, 1905. Serial No. 248,854.

To all whom it may concern:

Be it known that I, FRANCIS M. STAMBAUGH, a citizen of the United States, residing at St. Louis, Missouri, have invented a certain new and useful Improvement in Drill-Presses, of which the following is a full, clear, and exact description, such as will enable others skilled in the art to which it appertains to make and use the same, reference being had to the accompanying drawings, forming part of this specification, in which—

Figure 1 is a front elevational view of my improved drill-press. Fig. 2 is a side elevational view, partly in section, of the work-carrying table. Fig. 3 is a detail view of a stop for the table. Fig. 4 is a bottom plan view of the table. Fig. 5 is a side elevational view looking from the inside of the reversing mechanism. Fig. 6 is a detail view of the upper dog on the drill-shaft for actuating the mechanism to reverse said shaft. Fig. 7 is a view of the lower dog for throwing the drill-driving mechanism out of mesh. Fig. 8 is an enlarged sectional view through the dog, showing the torsional spring for holding the same in one position. Fig. 9 is a plan view of the reversing mechanism, the parts above the same being omitted. Fig. 10 is a horizontal sectional view through the reversing mechanism. Fig. 11 is a detail view of the dog-operated slide-bar. Fig. 12 is a sectional view on line 12 12 of Fig. 10. Fig. 13 is a sectional view through the lubricant-controlling mechanism. Fig. 14 is a side elevational view of parts of the same. Fig. 15 is a bottom plan view of said mechanism. Fig. 16 is a detail perspective view of the drill-shaft and a modified form of slide-bar, and Fig. 17 is a longitudinal sectional view through the slide-bar.

This invention relates to a new and useful improvement in drill-presses, the object being to arrange two or more presses side by side whereby work clamped on a suitable table could be successively operated upon in the performance of the several operations, such as drilling and tapping, which said work undergoes.

Another object is to provide means whereby the operator may after clamping the work in position set in action certain devices to cause the work-carrying table to progress step by step, so as to locate the work suc-

cessively under the various tools designed to act upon the work.

Another object is to place within easy reach of the operator controlling devices whereby one or more drill-presses may be started at the will of the operator, automatic mechanism being provided, so as to reverse the rotation of the drill-shaft to cause the same to recede after its work is done, said shaft being brought to a position of rest automatically.

Another object is to provide means whereby a lubricant is automatically supplied during the time that one or more of the tools is performing its work, said lubricant being automatically shut off when the drill-shaft is reversed and receding from the work.

With these objects in view the invention consists in the construction, arrangement, and combination of the several parts, all as will hereinafter be described and afterward pointed out in the claims.

In the drawings I have shown two drill-presses arranged side by side, with their tool-carrying shafts arranged over a table common to both of them. These drill-presses are of ordinary construction and, as usual, are supported upon posts 1. Referring to Fig. 1, it will be seen that the tool-carrying shaft 2 of one of these drill-presses is provided with an ordinary drill 3, and this shaft is thrown into gear with the driving mechanism by means of the lever 4. Other mechanism common to single drill-presses is also used to effect the feed of the shaft to cause the shaft to recede and to be brought to a position of rest. These are not shown in the accompanying drawings, as they form no part of my present invention.

5 indicates a work-table which, as shown in Fig. 2, is pivotally mounted in bracket extensions extending from the posts 1. This work-table is provided with the usual inverted-T-shaped slots for the attachment of the vise-clamps 6 for holding the work 7 in position. The work in this instance is a clevis designed for use particularly in air-brake-slack adjusters, and the operations performed upon this clevis are first drilling and then tapping. When the clamp 6 is brought to the front of the machine, as shown in Fig. 1, the operator adjusts the clevis in the clamp and then temporarily depresses the foot-treadle 8, which is

55

60

70

75

80

85

90

95

100

105

connected to a spring-pressed pin 9, (see Fig. 3,) coöperating with recesses 10 on the under side of the work-table. The operator next depresses a lever 11, which is connected to a 5 flexibly-mounted driven shaft 12, carrying a friction-gear 13 at its inner end. This friction-gear is thus thrown into contact with the under side of the work-table, causing the same to rotate until the pin 9 drops into the 10 next recess 10 in its path, in which position the clevis to be drilled is located in the proper position under the drill 3. The operator now moves the lever 4 to start the drill 3 on its work and at the same time raises the rod 14 15 identified with the other drill-press, so as to start the tap in its work on a drill-clevis 7^a, which by the advance of the work-table has been located thereunder. This advance of the work-table locks the finished clevis—to 20 wit, one which has been drilled and tapped—in front of the operator, who now removes the same from its clamp and introduces another clevis into position in the clamp to be operated upon. While the workman is doing 25 this drill 3 is performing its operation, and the tap is also performing its operation, so that by the time the operator adjusts a new clevis into position in the vise-clamp the work of the drill and tap has been finished and the operator may press the foot-treadle 8 and operate 30 the handle 11 to cause another advance of the work-table to locate the work under the respective tools to receive the above-mentioned operations.

35 I will now describe the automatic mechanism, which is set in operation by temporarily raising the rod 14.

15 is a tap mounted on a threaded tool-carrier the pitch of whose threads corresponds 40 to the cutting-threads on the tap. The threaded portion 16 of this tool-carrier operates through a fixed nut extending from the post 1 and effects the feed of the tap, as well as its recession, in a positive manner. This 45 threaded tool-carrier is connected to the drill-shaft 17, which shaft, as shown in Fig. 5, has miter-gears 18 and 19 loosely mounted thereon, said gears meshing with a driving-gear 20. Gears 18 and 19 have friction-faces 50 and coöperate with a double-faced clutch 21, splined on the drill-shaft and moved into engagement with one or the other of the gears 18 and 19 by means of a yoke 22, pivotally mounted in the head of the drill-press and 55 having a bell-crank extension in the form of a segmental gear 23. Meshing with the segment 23 is a segment 24, fixed to a rock-shaft upon which a rock arm or lever 25 is secured. It is obvious that if this lever 25 is raised to 60 the position shown by the dotted lines in Fig. 5 the clutch will engage the gear 19 and rotate the drill-shaft to the right, causing the threaded tool-carrier to drive the tap into the clevis and cut the thread. When the lever 65 is depressed, as shown by the dotted

lines, the clutch will be moved out of engagement with the gear 19 and into engagement with the gear 18, so that a reverse rotation will be imparted to the drill-shaft, causing the drill-tap to recede from the opening. The 70 positive advancing drive and recession of the drill-tap is advantageous in tapered openings, because the threads in the opening being tapped are not mutilated, as is frequently common to hand work of this character. 75

Lever 25 is provided with a bearing at its end, in which is adjustably mounted a pitman 26. This pitman is also connected to a crank-pin 27, mounted on a block 28, slidingly mounted in ways in a disk 29, said 80 block having a threaded opening for engaging an adjusting-screw 30, whereby the throw of the crank-pin may be increased or diminished. Disk 29 is provided with three recesses *a*, *b*, and *c* in its periphery and is joined to a gear 31 in mesh with a pinion 32, loosely mounted on a constantly-driven shaft 33. 33 receives motion through the medium of miter-gears. 85

34 indicates a clutch which has sliding engagement with the hub of pinion 32 by means of suitable keys, which insure coincident rotation of said parts. Springs 35 tend to slide the clutch member longitudinally of shaft 33 and into engagement with a companion clutch member 36, keyed to the end of shaft 33. The gear ratio between pinion 32 and gear 31 is four to one, one revolution of pinion 32 driving gear 31 one-quarter of a revolution. 90

The sliding spring-pressed clutch member 34 is provided with a cam-groove 34^a in its periphery, which groove, as shown in Fig. 9, does not extend entirely around the periphery, but has its ends separated by a stop-wall 105 34^b. An arm 37 is provided with a roller or projection at its end designed to coöperate with the cam-groove of the clutch, said arm 37 being a member of a bell-crank lever, whose other member 38 is provided with a projection coöperating with the periphery of the disk 29 and the recesses therein. The rod 14, before described, is mounted upon the outer end of this member 38. 110

The operation of the above parts is as follows: When rod 14 is raised, the arm 38 lifts its projection out of the recess *a*, and at the same time arm 37 lifts its projection out of the cam-groove, permitting the springs to force the sliding clutch member into engagement with the fixed and constantly-rotating clutch member, whereby motion is imparted, through the pinion 32, to the gear 31. Rod 14 is not held in its raised position, but is instantly released, so that the projection on 120 arm 38 rides on the periphery of disk 29. This holds the projection of arm 37 away from the cam-groove until the crank-pin 27 approaches its uppermost position, (indicated by 27^a.) The projection on arm 38 will drop 125 130

into the cam-groove *b* and in so doing throw the roller on arm 37 into the wide portion of the cam-groove in clutch 34, a continued rotation of said clutch causing the roller to engage the fluctuation in the cam-groove, which results in disengaging clutch 34 from its constantly-rotating companion 36. The parts are brought to a position of rest when the roller on arm 37 comes in contact with the wall across the cam-groove, and consequently momentum will not carry the parts beyond the designed position, the crank-pin being in its highest position at the time the parts are arrested, as indicated by the dotted circles 27^a. In this position of the crank-pin the arm 25 is raised and the clutch 21 thrown into contact with the gear 19, so as to drive the tool-carrier and its carried tap in the proper direction—to wit, downwardly—to form threads in the clevis.

Shaft 17 is provided with a collar 39, preferably adjustably mounted thereon and upon which collar is mounted a spring-pressed dog 40, which for the sake of distinction we will call a "stop-dog." Above collar 39 on shaft 17 is a similar collar 41, also adjustably mounted on said shaft, and which collar 41 carries a spring-pressed dog 42, which I will call a "reversing-dog."

43 indicates a slide-bar carrying a roller 44, which is located between the inclined faces of a block 45, mounted on the arm 38. Slide-bar 43 has a depending arm (see Fig. 11) to which are connected opposing springs 43^a, tending at all times to hold said bar 43 in a central position, but permitting said bar to be displaced in either direction. Suitable means are provided for regulating the tension of these springs. As shown in Fig. 11, bar 43 is also provided with a lateral extension at its end for coöperating with the dogs. Assuming that the shaft 17 is rotating in the proper direction and descending, the stop-dog will ride idly by the projection on bar 43 without operating said bar, and the shaft will continue to descend until the reversing-dog 42 engages the end of bar 43 and forces the same inwardly. The roller 44 will engage one of the inclines on bar 38, raising said bar, and with it the projection, out of the recess *b*. Of course the reversing-dog 42 passes beyond the projection on bar 43, permitting said bar to return to normal position; but before this return movement the sliding clutch has been thrown into engagement with the constantly-rotating clutch member and motion is imparted to the disk 29, so as to carry the recess *b* from under the projection on the bar 38. Thus when bar 38 descends its projection will ride over the disk 29 until the recess *c* is brought opposite, at which time the projection on bar 38 falls therein and the roller on arm 37 engages the cam-slot of the clutch and disengages the clutch members.

65 It will be noted that the recesses *b* and *c*

are diametrically opposite each other on the disk 29, and thus the pinion 32 makes two revolutions, causing the disk 29 to make one-half a revolution, locating the crank-pin 27 in its lowest position, as indicated by the dotted circles 27^b. In this lowest position of the crank-pin the clutch 21 is in engagement with the reversing-gear 18, and thus opposite rotation is imparted to shaft 17. In starting its upward movement the reversing-dog rides idly by the projection on bar 43 and the shaft 17 continues to ascend until the stop-dog 40 engages the projection on bar 43 and moves said bar outwardly. This outward movement causes the roller 44 to ride under the opposite inclined face of block 45 and raise the bar 38 so as to carry its projection out of the recess *c* and the roller on arm 37 out of the cam-groove of the sliding clutch. Disk 29 is now rotated until the projection on bar 38 drops into the recess *a*, in which position the crank-pin will be, as shown in full lines, arresting the bar 25 in a central position and clutch 21 in a similar or neutral position between the gears 18 and 19.

90 Splined on the shaft 17 is a gear 46, which permits said shaft to rise and fall in its operations, but compels the rotation of said gear. This gear meshes with a gear 47, (see Fig. 13,) which gear is conjoined to a friction-disk 48. 95 49 indicates a companion friction-disk mounted in the hollow shaft of gear 47, the stem of said disk 49 being threaded to receive jam-nuts coöperating with a lifting-spring 50, whose energy is directed at all times in forcing the friction-face of disk 49 into engagement with the friction-face of disk 48. 51 indicates a rotatable valve-rod coöperating with the disk 49, on the lower end of which rod is an appropriate valve arranged in the 100 casing 52, so that the valve is operated by the rotary movement of the valve-rod. The pipe 53 leads from a source of supply of lubricant to the valve-casing, and the pipe 54 leads from said casing to conduct the lubricant to the tap 15. 55 indicates a fixed stop having oppositely-inclined faces, with which coöperate the inclined ends of arms 56, mounted on the friction-disk 49. The operation of this construction is as follows: When shaft 17 is 105 rotated to drive the tap into the work, the gear 46 and its meshing gear 47 will of course be correspondingly rotated. Spring 50 has a tendency to lift friction-disk 49 and will readily cause the inclined face of the arm 56 to 110 ride off the fixed stop 55, so that the disk 49 will be rotated until the inclined face of its other arm 56 comes in contact with the opposite inclined face of the fixed stop 55, when said disk 49 and its valve-rod 51 will be arrested. This position of the parts opens the valve and supplies the lubricant through the tap. When the shaft 17 is reversely rotated to move the tap from the work, the direction 115 of movement of gear 46 will be reversed, and 120

125

130

consequently the disk 49 will be partially rotated in a reverse direction, so that the valve will be closed and shut off the supply of lubricant from the tap. The valve remains closed until the operator again releases the rod 14 to start the tap, when the valve is opened, said valve remaining open as long as the tap is doing work, but being shut off contemporaneously with the initial receding action of the tap and remaining closed while the tap is inactive.

In Fig. 16 I have illustrated the drill-shaft 17 with its spaced pawl-carriers 39 and 41 as coöperating with a modified form of slide-bar 15 for governing the actuating movement of the clutch mechanism. The slide-bar 43^a is illustrated as being provided with a transverse dovetailed groove 57, in which is adjustably arranged a vertically-movable slide 20 58, carrying a lug or projection 59 to be engaged by either the pawl 40 or the pawl 42. The slide-bar is provided with an elongated slot 60, through which projects a bolt 61, extending through the slide 43^a and having on 25 one end a thumb-nut 62, whereby the slide 58 may be held in any adjusted position. By providing the contact portion of the clutch-actuating device—to wit, the lug 59—the collars 39 and 41 and the slide 58 may be so 30 adjusted as to time the actuating movement of the slide 43^a so that the clutch mechanism will operate at predetermined periods.

I am aware that minor changes in the construction, arrangement, and combination of 35 the several parts of my device can be made and substituted for those herein shown and described without in the least departing from the nature and principle of my invention.

Having thus described the invention, what 40 is claimed as new, and desired to be secured by Letters Patent, is—

1. In a tapping-machine, a rotatable tap-driving shaft, and an actuating mechanism 45 therefor including a constantly-driven drive-shaft, spaced gears loose on the tap-driving shaft, a gear on the constantly-driven drive-shaft constantly in mesh with said gears, a splined clutch intermediate said gears, a lever 50 mechanism for actuating said clutch to throw it into engagement with either of said gears, a rotatable disk connected to said lever mechanism, means for rotating it, and means for temporarily preventing the rotation of said 55 disk; substantially as described.

2. In a tapping-machine, a rotatable tap-driving shaft, an actuating mechanism therefor including a constantly-driven drive-shaft, spaced gears loose on the tap-driving shaft, a 60 gear on the constantly-driven drive-shaft constantly in mesh with said gears, a splined clutch intermediate said gears, a lever mechanism for actuating said clutch to throw it into engagement with either of said gears, a 65 rotatable disk connected to said lever mech-

anism, means for rotating said disk, means for stopping rotation of the disk, and means actuated by the rotation of the tap-driving shaft for starting rotation of the disk; substantially as described.

3. In a tapping-machine, the combination 70 with a tap-driving shaft, spaced gears loosely mounted on said shaft, a clutch member splined to said shaft between the gears and movable into engagement with each of them alternately, a lever mechanism for alternately moving the clutch member into engagement with the respective gears, a disk for actuating said lever mechanism, a lever having a projection adapted to intermittently 75 engage with the disk to prevent its rotation, a pinion for driving the disk, means for driving the pinion, means on the lever for causing disengagement of the pinion and its driving means when the lever engages the disk, and 80 means for causing engagement of the pinion and its driver to drive the disk only when the projection on said lever is out of engagement with the disk; substantially as described.

4. In a tapping-machine, the combination 85 with a tap-driving shaft, spaced gears loose 90 on said shaft, a splined clutch member movable on said shaft and movable into frictional engagement with each of said gears alternately, means for alternately moving the 95 clutch member into frictional engagement with the respective gears, a disk for actuating said means, a lever-carrying means adapted to intermittently engage with the disk to prevent its rotation, a pinion for driving the 100 disk, means on the lever for permitting the pinion to drive the disk only when said lever is out of engagement with the disk, and means for throwing the lever out of engagement with said disk; substantially as described.

5. In a tapping-machine, the combination 105 with a tap-driving shaft, constantly-driven spaced gears loose on the tap-driving shaft, a splined clutch member interposed between 110 the gears and capable of engaging each of them to rotate the shaft alternately in opposite directions, mechanism for throwing the clutch into engagement with either of said gears and including a rotatable disk, means 115 for actuating said disk comprising a shaft, a loose pinion on said shaft, a clutch, one member of which is rigid with said shaft and the other with the pinion, means for connecting the pinion-clutch member and the shaft-clutch member, means for holding said clutch members out of engagement with each other, and for holding the disk against rotation including a lever, a sliding bar beneath the lever and having means for throwing the lever 120 out of engagement with the disk and with the clutch member on the pinion, and means on the tap-driving shaft for actuating the sliding bar; substantially as described.

6. In a tapping-machine, a reversible shaft 130

- provided with a tap, a tube for supplying a lubricant to said tap, means for controlling the flow of the lubricant to said supplying-tube, said means consisting of a valve, a valve-stem a friction-disk to which said valve-stem is connected, a coöperating friction-disk provided with a gear, a gear on the tap-carrying shaft meshing with the friction-disk gear whereby movement of said shaft in one direction opens the valve to permit the lubricant to flow through said tube, and a stop for arresting the movement of the valve-stem friction-disk after the valve has been opened, the movement of the shaft in the reverse direction closing said valve to cut off the supply of lubricant; substantially as described.
7. In a tapping-machine, the combination with a reversible tap-driving shaft, a lubricating-tube adjacent to the tapping end of the shaft, and lubricant-controlling means for automatically permitting a lubricant to flow through the tube only while the tap-driving shaft is rotating in one direction, said means comprising a valve, valve-stem and gear thereon, a spring-actuated clutch member and stop mechanism coöperating with the tap-driving shaft adapted to intermittently hold the gear on the valve-stem rigid therewith; substantially as described.
8. In a tapping-machine, the combination with a reversible tap-driving shaft, a tube for feeding a lubricant onto the work to be tapped, a valve for cutting off the supply of lubricant when the tap-driving shaft is rotating in one direction, means for actuating said valve comprising a valve-stem, a gear loose on said valve-stem, a gear on the tap-driving shaft and secured to rotate therewith, said gear being constantly in mesh with the loose gear on the valve-stem, a friction-clutch face on the valve-stem gear, a spring-actuated friction-clutch on the valve-stem and secured to rotate therewith, said last-mentioned clutch member being adapted to hold the valve-stem against rotation with respect to the gear on the valve-stem and means for limiting the rotative motion of said valve-stem; substantially as described.
9. In a tapping-machine, the combination with a reversible tap-driving shaft, a tube for feeding a lubricant onto the work to be tapped, a valve for cutting off the supply of lubricant when the tap-driving shaft is rotating in one direction, means for actuating said valve comprising a valve-stem, a gear loose on said valve-stem, a gear on the tap-driving shaft and secured to rotate therewith, said gear being constantly in mesh with the loose gear on the valve-stem, a friction-clutch face on the valve-stem gear, a spring-actuated friction-clutch on the valve-stem and secured to rotate therewith, said last-mentioned clutch member being adapted to hold the valve-stem from rotation with respect to the valve-stem gear, means for automatically relieving frictional contact of the two clutch members, said means comprising a bracket, a rigid projection on the bracket, and projections on the valve-stem clutch for engagement with the projection on the bracket; substantially as described.
10. In a tapping-machine, the combination with a reversible tap-driving shaft and mechanism for operating it, of a mechanism for feeding a lubricant to metal work comprising a tube, a valve in the path of the tube, a valve-stem, a gear loose on said valve-stem and having a clutch-face, means on the tap-driving shaft for actuating said gear, a spring-actuated clutch member for coöperating with the clutch-face on the gear, a rigid projection on a part of the machine with which the lubricating mechanism coöperates, and projections carried by the second-mentioned clutch member for engagement with the projection on the machine to move the second-mentioned clutch member out of frictional contact with the clutch member on the gear; substantially as described.
11. In a tapping-machine, the combination with a reversible tap-driving shaft and mechanism for operating it, of a mechanism for feeding a lubricant to metal work comprising a tube, a valve in the path of the tube, a valve-stem, a gear loose on said valve-stem and having a clutch-face, means on the tap-driving shaft for actuating said gear, a spring-actuated clutch member for coöperation with the clutch-face on the gear, a projection on the machine with which the lubricating mechanism coöperates, said projection having oppositely-inclined faces, and oppositely-disposed projections carried by the second-mentioned clutch member for engagement with the oppositely-inclined faces for moving the second-mentioned clutch member out of frictional contact with the clutch-faces on the gear; substantially as described.
- In testimony whereof I hereunto affix my signature, in the presence of two witnesses, this 3d day of March, 1905.
